UNITED STATES PATENT OFFICE.

LOUIS P. VALIQUET, OF NEW YORK, N. Y.

DESIGN FOR A CASE FOR TALKING-MACHINES.

SPECIFICATION forming part of Design No. 35,874, dated April 15, 1902.

Application filed March 19, 1902. Serial No. 99,030. Term of patent 7 years.

To all whom it may concern:

Be it known that I, LOUIS P. VALIQUET, a citizen of the United States of America, and a resident of the borough of the Bronx, city, county, and State of New York, have invented 5 a certain new and original Design for a Case for Talking-Machines, of which the following is a specification.

Figure 1 is a plan view of the case, shown 10 partly in dotted lines. Fig. 2 is a side elevation of the case in outline looking in the direction of either of the arrows 2 2 shown in Fig. 1. Fig. 3 is a side elevation of the case, partly shaded and partly in outline, looking 15 in the direction of the arrow 3 shown in Fig. 1; and Fig. 4 is a similar view looking in the direction of the arrow 4 shown in Fig. 1.

As shown in the drawings, the leading or 20 material features of my design are the panel 25 ornamentations, consisting on the one side of the representation of the pipes, trumpet, cymbals, and triangle tied together by a ribbon embossed, carved, or indented upon one of the panels, as shown in Fig. 3 at A, the representation of a lyre surrounded by a laurel-wreath and ribbon intertwined upon the opposite panel, as shown in Fig. 4 at B, and

the shield or tabard, as shown at C in Fig. 2, upon the two remaining panels. The top of the case is also provided with an ornamental 30 molding D, as shown in all the views, and at the base of each of the panels is a scroll E. The case is supported upon claw-feet F F, &c., placed at each corner, and these feet are continued upward in the shape of foliated 35 brackets G G, &c., which extend along the corners of the rectangular case H and overlap the edges of the side panels.

While my above-described design is particularly appropriate for talking-machine 40 cases, it may also be applied to music-boxes and cases or boxes for containing other articles.

Having therefore described my invention, what I claim as new, and desire to protect by 45 Letters Patent, is—

The design for a case for talking-machines, as herein shown and described.

Signed at New York city, New York, this 17th day of March, 1902.

LOUIS P. VALIQUET.
